(57) **CLAIM**

We claim the ornamental design for a display mount for a game controller, as shown and described.

DESCRIPTION

FIG. 1 is a top, right side, front perspective view of a display mount for a game controller, shown in an environment of use;

FIG. 2 is another top, right side, front perspective view thereof;

FIG. 3 is a left side elevation view thereof, the right side elevation view being a mirror image thereof;

FIG. 4 is a top plan view thereof;

FIG. 5 is a bottom plan view thereof;

FIG. 6 is a front elevation view thereof; and,

FIG. 7 is a back elevation view thereof.

The broken lines shown in FIG. 1 illustrate the environment of the claimed design and form no part thereof.

The break lines shown on the top portion of the display mount for a game controller illustrated in FIGS. 1-4 and 6-7 indicate that the appearance of any portion of the article between the break lines forms no part of the claimed design.

1 Claim, 7 Drawing Sheets
